WILLIAM A. DOBSON, OF BRIDGEPORT, CONNECTICUT, ASSIGNOR TO UNDERWOOD ELIOTT FISHER COMPANY, OF NEW YORK, N. Y., A CORPORATION OF DELAWARE

TYPEWRITING MACHINE

Application filed April 4, 1929. Serial No. 352,377.

This invention relates to typewriting machines, and more particularly to means for instantly connecting or disconnecting the ratchet-wheel and platen.

5 In portable typewriting machines, the platen-carriage just fits between the sides of the carrying case cover. In constructing the present invention, it is aimed to arrange the mechanism so that the width between the left 10 and right platen knobs, which are the extreme outer ends of the platen-carriage, should not be extended.

For this purpose, the releasing mechanism is constructed to fit between the platen and 15 the left-hand carriage-end plate; and for compactness the releasing mechanism is constructed to extend within the platen, so that the entire mechanism takes up only a small amount of space outside of the platen.

20 Shortening of the typing line has been avoided, while the distance between the carriage-end plates has remained the same.

The construction requires practically no changes in the standard construction of the 25 Underwood portable typewriter-carriage.

Another feature is that the clutch-mechanism may be operated from either side of the carriage by merely operating either the left or right platen-knob.

30 In these portable typewriters the length of the carriage is limited, while the platen is constructed as long as possible, so as to accommodate a wide sheet. In devising the present invention it was necessary that the carriage 35 should not be lengthened, and that the writing line should not be shortened, and furthermore that the usual wide sheet should still be filled out with typed lines. The clutch-releasing mechanism takes up only the space between 40 the platen and the line-space ratchet-wheel, which, in the present invention, forms the outer end of said clutch-mechanism.

There is used a slidable platen-shaft carrying the platen-knobs. Movement of the shaft 45 is one direction wedges apart the clutch-segments, which engage and bind a drum provided on the ratchet-wheel.

When the platen-shaft is moved in a reverse direction, the wedging means will release the 50 clutch-segments from the drum of the ratchet

wheel, which disassociates the platen therefrom, and permits independent spacing of a work-sheet. Through the simplicity of the clutching means employed, it is necessary to exert but a slight pressure on opposite platen- 55 knobs, in order to alternately make the ratchet-wheel effective or ineffective. It is tantamount also that instead of pressing on opposite knobs, the same results are accomplished by alternately pressing and pulling 60 on only one knob. For this reason the connection or release of the ratchet-wheel can be easily controlled from that end of the carriage which is most convenient to reach.

Another feature of this invention lies in the 65 double function incorporated in the wedge, which forces the clutch-segments apart, and concomitantly locks them in tight frictional engagement with the ratchet-wheel drum. Due to the springiness of said segments, the 70 wedge sets up tension therein, which aids in increasing the friction by slightly flattening the curves and increasing their holding area. Said springiness also causes the segments to better fill out any inequalities on the inner 75 surface of the drum, and thus helps to maintain frictional engagement.

Another feature of this invention lies in the 80 use of a retaining pin which acts as a fulcrum for the wedge, and also holds the clutch-segments in effective alignment therewith. In assembling the pin and the wedge, the latter is bored to have a driving fit for the pin, whereby the pin is held after insertion. In 85 order to permit rotation of the pin when the wedge is swung, the pin-retaining holes of the segments are bored somewhat larger than the pin. These larger holes also provide clearance for the segments, so the latter can move along the pin when spread or released 90 by the wedge.

Other features and advantages will hereinafter appear.

In the accompanying drawing, 95 Figure 1 is a partial longitudinal section through a platen and its supports, and shows the parts of this invention as related when the ratchet-wheel is ineffective.

Figure 2 is a perspective view of a portion 100 of a platen, and shows some of the parts of

this invention associated therewith, and partially broken away.

Figure 3 is a partial longitudinal section through a platen, and shows parts of this invention as related when the ratchet-wheel has been made effective.

Figure 4 is a detail of parts of the clutch, and shows the segments forced apart by the wedge.

10 Figure 5 is a similar view to Figure 4, but with the wedge partially withdrawn to permit the release of the ratchet-wheel.

Figure 6 is a perspective view of parts of this invention, and in proper relationship for 15 assembly.

Figure 7 is a perspective view of parts of this invention, and shows the adjustable device for raising or lowering one end of the platen-shaft.

20 Figure 8 is a perspective detail of the pivoted wedge, the amount of slope in the wedged faces being indicated in dot and dash.

Referring to the drawing, 10 and 11 are 25 end frames of a platen-carriage, which form part of a typewriter, not shown. The frame 10 has a countersunk hole 12, in which is inserted a journal 13. The latter has a shoulder 14 and a turned-down portion 15 which is riveted to the frame. The frame 11 has a 30 clearance hole 16 and an approximately horizontal slot 17 through which projects a set-screw 18 that is threaded into a block 19. The latter is slidable between two lugs 20 which are attached to or are integral with 35 the frame 11.

In the block 19 is an inclined slot 21, in 40 which can slide the rounded head 22 of a lever 23 which is attached to the frame 11 by a pivot 24. The lever 23 has a countersunk 45 hole 25 in which is inserted a journal 26. The latter has a shoulder 27 and a turned-down portion 28 which is riveted to the lever 23. The journal 26 supports a platen-shaft 29 which is slidable therethrough, and which 50 has a flattened area 30. The latter is abutted by a set-screw 31 which attaches a platen-knob 32 through means of a connected hub 33.

A set-collar 34 is mounted on the journal 55 26 and adjustably abuts a hub 35 which forms part of a usual end plate 36. The latter is attached by screws 37 to a core 38 which forms part of a platen 39. The latter also has an end plate 40 which is attached to said core by screws 41. Said end plate 40 is formed 60 with an inwardly-extending barrel 42 which is axially bored and in which can slide a cylinder 43. The latter has a beveled end 44 to remove any burr that might impede the sliding of said cylinder.

65 The cylinder 43 is axially bored as at 45 to support an end of the platen-shaft 29 which is fixed therein through means of a pin 46. Said cylinder also has a larger axial boring 47 which lightens its weight and provides clearance as will appear. The cylinder is

slidably supported in the journal 13 and is tightly held in a hub 48 of a platen-knob 49. A pin 50 can also be used to hold said cylinder in said hub. The cylinder has a channel 51, at one end of which is a hole 52 that extends through the wall. 70

The end plate 40 has a hub 53 which tightly fits inside an end of the core to center and help support the same. The fixity of the two is also furthered by a shoulder 54 which abuts 75 the end of said core. The end plate 40 also has an annular bearing surface 55, a shoulder 56 and two hubs 57 and 58. The bearing surface 55 supports one end of a rotatable drum 59 whose other end is turned down and riveted over an inner beveled edge of a ratchet-wheel 60. A plate 61 is driven onto the hub 58 to abut the end of the hub 57 which stops it. The plate 61 also has an annular bearing surface 62 around which said 80 drum can rotate and which is retained thereon by a shoulder 63.

The plate 61 has a countersunk hole for a screw 64 which has a shank 65, a shoulder 66 and a threaded portion 67. The latter is 90 screwed into a threaded hole 68, in the end plate 40. The counter-sinking of the screw 64 prevents the head from hitting extraneous parts when said plate is rotated, while the shoulder 66 limits the thrust and prevents 95 the shoulder 63 from pinching the drum and arresting or retarding its rotation. The shank 65 also serves as a fulcrum for clutch-segments 70 which have approximately semi-circular channels 71 that fit thereon. 100

The clutch-segments 70 can swing radially between the drum 59 and the hub 57. The latter also serves to space the plate 61 from the shoulder 56 which provides side clearance for the swing of said segments. The latter have holes 72 at one end that are larger than a retaining pin 73 which they encompass. The segments therefore can swing radially a sufficient distance before being stopped by said pin. At the ends having the holes 72 110 the segments are formed with cam-surfaces 73^a which normally lie at an angle to each other and will abut a wedge 74.

The wedge 74 has a hole 75 of such diameter as will retain the pin 73 when positioned 115 therein. When assembled the holes 72 will fulcrum said pin as the wedge is rotated through an attached lever 76. The pin also serves to maintain the wedge and the segments 70 in effective relative positions. The lever 76 has a beveled end 77 and a rounded nose 78. Said bevel permits the lever to slide along the channel 51 during assemblage of the various parts of this invention. Said 120 rounded nose presents a smooth surface to the side of the hole 52 so as to slide easily when said side actuates the lever. During such movement the lever projects through said hole and into the clearance space 47.

125 In forming the plate 61 the inner edge has 130

a cut-out 79 to permit swinging of the lever 76. For the same reason the end plate 40 also has a cut-out 80. In addition there is a spacing collar 81 between the frame 10 and the end of the hub 58. Said collar maintains a clearance space for parts of the pawl, not shown. A spring-pressed detent 82 is also shown, as well as a type-head 83. The spacing lever and associated parts, while used with this invention, are common, and for this reason have not been shown.

In assembling the parts of this invention the components of the bearing on the end plate 11 can be installed first. The platen is then mounted on its end plates, while the ratchet-wheel and clutch-members are placed in relative association with the end plate 40. The screw 64 is then threaded into the hole 68 to secure the plate 61, and is fixed by tight abutment of the shoulder 66 against the end plate 40 which has previously been inserted and adjusted for this purpose. The knob 49 and the platen-shaft 29 having been attached to the cylinder 43, these unified components are successively run through the journal 13 and the spacing collar 81.

As the platen-shaft passes the collar 81 it is run through the platen, which at this time is held centered between the journals 13 and 26. During the transition of the unified shaft, the inwardly-projecting lever 76 will slide along the channel 51 until the nose 78 abuts the end thereof. The set-collar 34 can then be adjusted to abut the end plate 36 to hold the end plate 40 in rotatable abutment with the spacing collar 81. Without disturbing the relative positions of the cylinder 43 and the lever 76, the knob 32 is attached to the platen-shaft and in the position shown in Figure 1.

The platen having been mounted in the carriage, it is adjusted if necessary to bring its axis parallel to the line of typing. This is usually accomplished, as previously mentioned, through means of the block 19. It is not wished, however, to limit this invention to the use of only one block, because the same adjusting device in modified form can also be installed at the other end of the carriage. With said device at each end of the carriage it is then possible to fix the platen in various horizontal planes, and thus vary the angle at which the platen-surface is struck by the type.

55 Besides spreading and locking the clutch-segments apart, the wedging means maintains the associated cylinder and end plate in fixed rotative relation. This is accomplished by the lever of the wedge which passes through the walls of said cylinder and plate. As the lever requires but slight clearance to swing through said walls, lost motion is minimized when the superposed members are rotated by the cylinder. For this reason the dwell of said plate is negligible when actuated by the

lever and they rotate in unison. Therefore during rotation of the released clutch-members, the wedge does not creep to press a segment against the drum, and the ratchet-wheel remains ineffective.

70 The drawing illustrates this invention as applied to a portable typewriter having a platen-shaft of small diameter. Due to the latter, the cylinder 43 is used to provide an enlarged end that can be machined and still have structural strength. Because the cylinder supports one end of the platen, it forms part of the platen-shaft, and if omitted will not nullify this invention. When omitted, a larger shaft is used, the channel 51 is eliminated, the clearance space 47 and hole 52 are incorporated, the cut-out 79 is deepened and the lever 76 is lengthened. The assembling is then virtually the same excepting that before final lengthwise setting of the shaft, said lever is projected into said space 47. This invention therefore is adaptable to large machines and it is not desired to limit it to the design illustrated.

80 Variations may be resorted to within the scope of the invention, and portions of the improvements may be used without others.

85 Having thus described my invention, I claim:

1. In a typewriting machine, the combination with a platen and a shaft, of a line-space wheel freely rotatable about said shaft, a clutch-mechanism to connect said line-space wheel with said platen and including a drum secured to said line-space wheel, a pair of 90 expansible grips having a driving connection to the platen and curved to conform with the inner periphery of said drum, a wedging arm pivotally mounted between two adjacent ends of said grips, said arm having at one end a 95 pivot journaled in said grips, means engaging the other end of the arm with said shaft for rotary transmission thereby, and actuating means for swinging said arm longitudinally to expand said grips, thereby causing 100 the grips to engage the line-space-wheel drum, and allow the shaft to rotate the line-space wheel together with the platen.

110 2. In a typewriting machine, the combination with a platen having platen-ends confined between the ends of a platen-frame, of a shaft axially shiftable in said platen-ends, a line-space wheel adjacent one end of the platen and freely rotatable about said shaft, a clutch-mechanism to connect said line-space wheel with said platen and including a drum secured to said line-space wheel and rotatable upon the adjacent platen-end, a pair of grips having beveled adjacent tips and curved to 115 conform with the inner periphery of said drum, a member rigid upon said platen-end and upon which one end of said grips may be fulcrumed, an arm opposite to the fulcrum-point and pivotally mounted between the other ends of said grips and having a wedg- 120 125 130

- ing surface to engage said beveled tips, and means upon said shaft to control said arm as the shaft is shifted to expand said grips by a wedging action, thus causing the same 5 to engage the drum, said arm co-operating with said controlling means to form a coupling connecting said shiftable shaft to said grips, effective to allow the shaft to rotate the platen.
- 10 3. In a typewriting machine, the combination with a platen having platen-ends confined between the ends of a platen-frame, of a shaft axially shiftable in said platen-ends, said shaft effective to rotate the platen in every axial shift position of the shaft, a line-space wheel rotatable about said shaft, a drum 15 rotatable together with said line-space wheel about said shaft, expansible grips operable to bear against said drum to engage said line-space wheel, a wedge-member pivotally mounted between two adjoining ends of said grips to cause said grips to engage said drum, said shaft having a recess in which the free end of said wedge-member may lodge, so that 20 it may be swung between operative and idle position as the shaft is shifted, said wedge-member, in combination with said recess, serving to rotate said grips together with said shaft.
- 25 4. In a typewriting machine, the combination with a platen, a shaft, and line-space mechanism including a disengageable line-space wheel adjacent one end of said platen and rotatable relatively with said platen and 30 shaft, of a clutch-mechanism connecting said platen and line-space wheel, including a drum secured to said line-space wheel, grips curved to conform with the inner periphery of said drum, an arm pivotally mounted between said 35 grips and provided with a wedging surface, means on said shaft to swing said arm about its pivot and cause said wedging surface to press said grips against said drum, and a groove in said shaft to receive the free end of 40 said arm and form a path therefor, to permit the shaft to be removed from said mechanisms.
- 45 5. In a typewriting machine, the combination with a platen, a shaft slidably mounted 50 within said platen, and a loose line-space wheel adjacent one end of said platen and rotatable relatively with said platen and shaft, of a clutch-mechanism connecting said platen and line-space wheel, including a drum secured to said line-space wheel, grips having beveled adjacent tips and curved to conform with the inner periphery of said drum, an arm pivotally mounted between said grips, and having wedging portions to co-operate 55 with said beveled tips, said arm forming a driving connection between said platen and shaft, when the latter is rotated, but permitting free horizontal movement in both directions of said shaft with respect to said platen, 60 and means on said shaft co-operating with 55 said arm in each direction of said horizontal movement, to alternately connect and disconnect the line-space wheel from said platen.
6. In a typewriting machine, the combination of a platen, a longitudinally-adjustable shaft supporting the same, a line-space wheel normally connected in operative engagement with said platen to rotate the same, a clutching device mounted on the shaft, a controller therefor, effective to engage and disengage 70 the wheel from the platen at will, and a pair of shoulders on said shaft, one at each side of the controller, to control the operations of the clutching device by the longitudinal reciprocating movements of said shaft, by direct mechanical engagement with said clutching-device controller, said shaft also including means effective to rotate the platen when the latter is disengaged from said wheel.
7. In a typewriting machine, the combination of a platen, a shaft supporting the same, means for line-spacing the platen by the shaft, including a toothed wheel, a clutch mounted on the platen, effective to engage and disengage the wheel with reference to 80 said platen, said clutch including a lever pivoted at one end thereto, effective to operate the clutch, and a recess in the shaft to receive the other end of the lever to engage the lever with the shaft for swinging the lever into clutch engaging and disengaging position alternately thereby, and effective to engage the platen with said shaft for rotation in both 85 positions of the lever.
